ABSTRACT OF THE DISCLOSURE

A heater for melting ice and snow from railway switching rails. Combustible gas is released at intervals inside an elongated burner chamber made up of a surrounding hood and plate which are spaced apart to form an air intake opening along the bottom of the chamber and an upper combustion throat adjacent the rail to be heated. A shield adjacent the chamber provides protection against "flame out" due to wind gusts.

This invention relates to an improved arrangement for melting ice and snow which may collect around the moving and fixed rails of railway track switching apparatus.

Ice and snow which collects between and around the movable points of a railroad switch, if accumulated in sufficient quantity, may render the switch inoperable. Manual removal of such an accumulation is a laborious task consuming a substantial amount of time during which the switching yard is out of operation. Rail heating arrangements have accordingly been devised in order to melt the accumulated ice and snow and to prevent such accumulation.

In conventional rail heating systems, high pressure gas is piped along the rail and openings in the gas-carrying conduit direct gas jets toward the ball and web of the rail. The use of high pressure gas enables the flame to be accurately directed even in the presence of wind currents.

High pressure heating systems do, however, possess significant disadvantages. Combustible gas is normally not available at high pressures at the railroad yard; consequently, auxiliary equipment must often be used to increase the pressure of the gas supplied to the rail heaters. The localized, high-intensity flames produced in a high pressure system create a possibility that the flames may ignite adjacent railroad ties or inflammable portions of rolling stock which may park over the burners.

It is accordingly an object of the present invention to provide an improved, low-pressure railway switch heater which produces an evenly distributed, gentle flame along the length of the rail.

Low pressure heating systems have heretofore been subject to flame-out caused by wind currents and turbulence. Such flame-outs render the burner temporarily inoperative until the gas can be re-ignited. In addition, because the combustible gas used may be heavier than air, the unburned gas may form in pools thereby creating a fire hazard.

It is accordingly a further object of the invention to provide an improved low-pressure railroad switch heater which is substantially immune to flame-out caused by wind currents and turbulence.

In the principal aspect, the present invention takes the form of an arrangement for melting collected ice and snow from railway switching rails. A gas carrying conduit spaced apart from and substantially parallel to the rail to be heated is supplied with low-pressure gas. Jet holes drilled at intervals along the conduit supply the unburned gas to a burner chamber formed by a surrounding hood and plate. The cross-sectional shape of the burner hood may take the form of an "inverted-J" in which the arcuate

2

portion of the hood surrounds and is spaced from the conduit and the downwardly depending portion of the hood is positioned to extend below the conduit. A burner plate is mounted at an angle to and spaced from the downwardly depending portion of the hood to form an intake air opening between the bottom edge of the plate and the downwardly extending portion of the hood. According to a feature of the invention, the upper edge of the plate is parallel with and is spaced from the edge of the arcuate portion of the hood to form a longitudinal venturi throat adjacent to the rail. This venturi throat directs the flame to the ball and web of the rail, tends to hold the flame against blow out, and produces a short, intense flame. According to a further feature of the invention, a burner shield lying in a plane substantially parallel to the plane of the downwardly depending portion of the hood and spaced apart from the hood allows air to enter the burner chamber but provides protection against wind currents. The burner shield enhances the heating ability of the arrangement by causing recirculation of the heated combustion products of the flame to shorten the flame and increase the burning efficiently. According to a still further feature of the invention, spacing members placed at intervals between the burner hood and burner plate insure precise aperture widths for both the venturi throat and the air intake.

Ignition of the gas-air mixture appearing at the venturi throat is accomplished even in high winds by the provision of an ignition cup. A raw pilot-gas jet is injected into the cup so that turbulent mixing occurs. A spark plug, glow coils, or other form of igniter may be employed to produce the initial flame within the ignition cup, which then propagates along the length of the venturi throat. Means may be employed for re-energizing the igniter in response to any flame loss.

These and other features, objects and advantages of the present invention may be more clearly understood by considering the following detailed description. In the course of this description, reference will be frequently made to the attached drawings in which:

FIGURE 1 is an exploded perspective view of a switching rail heater which embodies the principals of the invention;

FIGURE 2 is an elevational view with a portion of the burner shield broken away to show the details of the rail heater in the neighborhood of the ignition cup;

FIGURE 3 is a cross-sectional view of the rail heater taken substantially along the line 3—3 of FIGURE 2; and

FIGURE 4 is a cross-sectional view of the rail heater taken substantially along the line 4—4 of FIGURE 2.

The arrangement contemplated by the present invention is a distributed line or "ribbon" type gas burner, which is adapted to heat an elongated section of rail—typically 11 to 17 feet long. The rail section to be heated, shown generally in FIGURE 1 at 11, is of typical shape and includes an enlarged upper portion or "ball" 12, an intermediate vertical "web" 13, and a horizontally flared base section 14.

Mounting holes are drilled through the web 13 at approximately twenty inch intervals as shown at 16. A bolt 18, washer 19, lock washer 20, and nut 21 are used to affix the lower L-shaped member 23 of a bracket assembly to the web 13 of the rail. As shown best in FIGURE 4 of the drawings, the stud 18 passes through a longitudinal slot in the bracket member 23. The horizontal slot permits the bracket member 23 to be positioned in various vertical positions. When the bracket member 23 is bolted in position flush against the web 13, an upper L-shaped bracket member 24 is permitted to move toward and away from the web 13 through the provision of an elongated slot of the outwardly extending flange of the member 23. A stud 27, washer 28, lockwasher 29 and a nut 30 are tightened

to hold the upper and lower bracket members 23 and 24 respectively together. The upwardly extending flange on the upper bracket member 34 is provided with a horizontally oriented elongated slot through which passes a Nelson stud 33 which is welded to the back of a burner hood 35. A washer 36, a lockwasher 37 and a nut 38 affix the hood 35 to the bracket member 24.

The Nelson stud 33 is sufficiently long to extend well beyond the member 24 in order to provide a point to which a burner shield 40 may be affixed. A washer 41 is placed between the burner shield 40 and the nut 38 while a lock washer 43 and a nut 44 are tightened to hold the burner shield in place.

It should be understood that while only one mounting bracket assembly has been described in detail, these assemblies are placed in intervals along the lengths of the rail heater to provide adequate support for the burner. The longitudinal slots which are incorporated into the L-shaped mounting bracket members 23 and 24 allow substantial relative movement between the rail and the mounted burner assembly, thereby permitting accurate placement of the flame even though the mounting holes in web 13 may not have been accurately positioned.

As best shown in FIGURE 5 of the drawings, the burner chamber itself is formed by the combination of a burner hood 35 and a burner plate 45. The burner hood 35 includes an arcuate portion shown generally at A which surrounds and is spaced from the top of gas carrying conduit 39 and a downwardly extending portion shown generally at B which is supported by the upper mounting bracket 24. The angle shaped burner plate 45 is mounted at an angle to and spaced from the downwardly depending portion of the hood 35 to form an air intake opening between the bottom edge of the plate 45 and the hood 35. The long dimension of the upper edge C of the burner plate 45 is parallel with and spaced apart from the long dimension of the edge D to produce an elongated throat. The planes of these two edges form an acute angle with one another to create a venturi effect at the elongated throat. Gas is carried down the conduit 39 and is ejected through angle drilled jet openings of the type shown at E which are positioned adjacent to the venturi throat. These jet holes are preferably drilled tangential to the inside circumference of the conduit 39 as shown in FIGURE 5.

Proper flow of combustion air and good mixing of gas and air are aided by the non-radial drilling of the jet openings as shown at E in FIGURE 5. Good air flow inside of the mixing chamber is enhanced by spacers 47 and 48 which insure properly proportioned air passages. The spacer 47 is directly welded to the burner hood 35 while the spacer 48 is welded to the burner plate 45. These spacers are positioned together and welded (typically at 6 to 12 inch) intervals along the length of the burner assembly. The jet openings E may be spaced at intervals (e.g. 1 to 2 inches apart).

The burner shields 40 are positioned as low as possible. If desired, the shields may rest on the wooden cross ties. In this position, most of the air enters at the top through the spacing between the shield 40 and the downwardly extending portion of hood 35. The resulting enclosed chamber serves to concentrate the heat at the web of the rail and enhance smooth air flow into the venturi throat formed at edges C and D and permits recirculation of some of the products of combustion to the air intake.

As shown in FIGURES 1 and 2 of the drawings, the conduit 39 is split in the middle with a T-joint 50 to which is connected a piping assembly 51. Gas is supplied to the conduit 39 from an available source through the piping assembly 51. Due to the novel configuration employed, this gas need not be supplied at high pressure—pressures as low as 10 inch water column being sufficient. An aperture 54 is cut into the right hand burner shield 40 to permit passage of the piping assembly 51.

The burner hood 35 and burner angle 36 are cut away in this central portion of the heater to allow room for an

ignition assembly which includes an ignition hood 60 and an ignition cup 61. A pair of Nelson studs 57 and 58 are welded to the two sides of the burner hood 35 in order to mount this ignition assembly.

As shown in FIGURE 2 of the drawings, the ignition cup 61 is positioned immediately below the conduit 39. As shown in FIG. 1, one wall of the cup 61 is formed by the ignition hood 60 to which the cup 61 is welded. A vertically drilled jet opening not (shown) in conduit 39 injects a raw gas jet into cup 61. A spark plug 65 is positioned within a mounting aperture in the ignition shield 60 such that the spark gap of plug 65 projects into the ignition cup 61. The air and gas mixture in ignition cup 61 is ignited by applying a high voltage to the spark plug 65 by way of a conductor 66 which is connected to the secondary output winding of a transformer 67 shown in FIGURE 1. The transformer 67 is placed inside a protective housing having side and bottom walls 70 and a top 72. A sealing gasket 73 is sandwiched between the top 72 and the housing 70 to prevent entrance of moisture. The housing 70 is fastened directly to the ignition shield 60 by means of a pair of extended stabilizing rods 74 and 75. A spacing block 76 made of ceramic material or the like and having a longitudinal passage therethrough serves to insulate the transformer 67 from heat transfer from the burner assembly, protects the high voltage conductor 66 from damage, and prevents inadvertent contact by operating personnel with the dangerous voltage appearing on conductor 66. A rubber shroud 80 protects the electrical connection between the spark plug 65 and the high voltage conductor 66.

The primary of transformer 67 is energized by the voltage on conductors 81 through a thermostat 82 which is affixed to the inside of the housing 70. The thermostat 82 is provided with a remote sensing element 83 which is held in the flame produced by the burner. The sensing element 83 opens the primary circuit of the transformer 70 whenever the flame is present and closes the primary circuit to cause sparking at the gap in spark plug 65 whenever the flame is absent. In this manner any flame-out is automatically sensed to cause re-ignition.

It is to be understood that the embodiment of the invention which has been described is merely illustrative of one application of the principles of the invention. Numerous modifications may be made by those skilled in the art without departing from the true spirit and scope of the invention.

What is claimed is:

1. An arrangement for melting collected ice and snow from a railway switching rail which comprises, in combination,

a gas-carrying conduit spaced apart from and substantially parallel to the long dimension of said rail, jet holes drilled at intervals along said conduit, means for supplying pressurized combustible gas to said conduit,

an elongated burner hood having an upper portion which surrounds and is spaced from the top of said conduit and a downwardly depending portion which extends below said conduit,

an elongated burner plate mounted at an angle to and spaced from said downwardly depending portion of said hood to form an air intake opening between the bottom edge of said plate and the downwardly extending portion of said hood, the upper edge of said plate being spaced apart from the edge of said arcuate portion of said hood to form a longitudinal throat adjacent to said rail, and means for igniting the gas-air mixture appearing at said throat.

2. An arrangement as set forth in claim 1 including an elongated burner shield which is mounted substantially parallel to and spaced from the plane of the downwardly depending portion of said hood on the side of said hood opposite from said rail, whereby combustion products are recirculated to said air intake.

3. An arrangement as set forth in claim 1 wherein the burner hood is spaced from the rail and the plane of the upper edge of said plate forms an acute angle with the plane of the edge of said arcuate portion to provide a venturi effect at said throat which helps to prevent blow out of the flame of the burner and which is located adjacent the rail.

4. An arrangement as set forth in claim 3 wherein said conduit is cylindrical and wherein said jet holes are drilled tangential to the inner circumference of said conduit.

5. An arrangement as set forth in claim 1 wherein said means for igniting the air-gas mixture appearing at said throat comprises, in combination,

a cavity positioned adjacent to said conduit,
an opening in said conduit for injecting a gas jet into 15
said cavity, and

electrical igniting means mounted within said cavity
for igniting the gas within said cavity.

6. An arrangement for heating a railway switching rail which comprises, in combination,
a source of a combustible gas,
an elongated conduit connected to said source,
an elongated hood member having the cross-sectional 20
shape of an inverted J,
support means for mounting said hood such that its
long dimension is parallel with said conduit, its upper 25
arcuate portion is positioned above, around, and spaced from said conduit and its downwardly depending portion extends below said conduit,
an elongated plate mounted at an angle to the plane 30
of the downwardly depending portion of said hood,
the lower edge of said plate being spaced from said
downwardly depending portion to form an air intake,
the upper edge of said plate being parallel with and 35
spaced from the edge of said arcuate portion to form
an elongated throat,

jet holes provided at intervals along said conduit for
directing said gas toward said throat, and

means for igniting the gas-air mixture appearing at said throat.

7. An arrangement as set forth in claim 6 wherein said elongated throat is positioned parallel with and spaced from said rail.

8. An arrangement as set forth in claim 7 including a burner shield which is mounted substantially parallel to and spaced apart from said downwardly depending portion of said hood on the side of said hood opposite from said rail to cause combustion products produced at said throat to recirculate to said air intake.

9. An arrangement as set forth in claim 8 wherein the plane of the upper edge of said plate forms an acute angle with the plane of the edge of said arcuate portion to produce a venturi effect at said throat.

10. An arrangement as set forth in claim 9 wherein said conduit is cylindrical and wherein said jet holes are drilled along a tangent to the inner circumference of said conduit.

11. An arrangement as set forth in claim 6 wherein said means for igniting the air-gas mixture appearing at said throat comprises, in combination,

a cavity positioned adjacent to said conduit,
an opening in said conduit for directing a jet of gas
into said cavity, and
electrically energized igniting means for igniting the
gas in said cavity.
